UNITED STATES PATENT OFFICE.

FREDERIC W. HILLARD, OF TOTTENVILLE, NEW YORK.

PAPER FINGER FOR TYPEWRITING MACHINES.

1,408,003.

Specification of Letters Patent. Patented Feb. 28, 1922.

Application filed March 7, 1921. Serial No. 450,204.

To all whom it may concern:

Be it known that I, FREDERIC W. HILLARD, a citizen of the United States of America, and a resident of Tottenville, New York, 5 have invented certain new and useful Improvements in Paper Fingers for Type-writers, of which the following is a specification.

My invention is an improvement in type- 10 writing machines, relating particularly to the paper holding fingers which serve to press the work sheets to the platen to a point considerably above the printing line.

The supports for my paper fingers are of 15 the overhung type. That is to say, they are pivotally supported at the rear of the platen and extend forwardly carrying the paper fingers down in front where they overlie the platen at the edges of the work 20 field and press up the work sheets at the printing line to conform to the cylinder.

While the paper finger of the type described, must of necessity overlie the edges 25 of the work sheets to press them against the platen, their supports must not arrest the further feed of the sheets. Hence, the supports for the paper fingers must be placed outside the field of the work sheets.

One serious difficulty which has heretofore existed with this device as heretofore 30 made, is that in carbon work, it is quite difficult to withdraw the work sheets temporarily for purpose of correcting all carbon copies, as is commonly done during the 35 course of the writing. This difficulty arises from the fact that the paper finger carrying arms extend inwardly from without the field of the work sheets on either side, into such field and overlap the work sheets, so 40 that the open space between the two paper fingers is materially less than the width of the work sheets. Both the finger carrying arms as heretofore made, which thus extend inwardly from right and left have been 45 made rigid on the supports, being integral therewith. Hence the carbon copies to be corrected, must be drawn forwardly out from under the paper fingers (which are made liftable for the purpose) or the sup- 50 ports must be moved sideways away from each other on their pivotal supporting rod to draw the fingers wholly outside the work field.

In order to overcome these objections, I have made my carrying arms separately 55 from the supports, instead of as heretofore, integral therewith and have provided hinged joints between the carrying arms and their supports, and spring-pressed locking means to restrain said hinges from operating while the paper fingers are in their work sheet controlling positions and have provided hand-operated means to unlock the hinge joints to swing the paper fingers out of the field of the work sheets. The 60 spring-pressed locking means also act as means for automatically relocking the carrying arms when returned into the field of the work sheets and into their right and left hand holding positions. 70

For convenience, I show my device applied to a modified Underwood typewriter. But it will be understood that the invention is capable of wide application on various makes of typewriters, and I accordingly 75 do not intend to limit it to use on the particular machine herein shown.

In the drawings, which form a part of this specification,—

Figure 1 is a plan view of the carriage 80 and a portion of the machine on which it is mounted.

Figure 2 is a sectional view on line X—X of Figure 1.

Figure 3 is a front view of the right hand 85 finger in raised position, with the paper finger cut away and shown in section.

Figure 4 is a plan view and in full lines shows the paper finger swung into inoperative position, out of the field of the work 90 sheets, and in dotted lines, shows the paper finger in operative position, in the field of the work sheets.

Figure 5 is a plan view of the device in the position shown in Figure 3, showing the 95 paper finger in inoperative position, out of the field of the work sheets.

Figure 6 is a fragmentary plan view with the device in operative position.

Figure 7 is a perspective view of the de- 100 vice showing the finger in inoperative position.

Figure 8 is a front view of the carriage, showing a modified pair of paper fingers in operative position, in the field of the work 105 sheets.

Figure 9 is a perspective view of the modified paper finger of Figure 8.

Upon the carriage 1 is mounted the platen or paper cylinder 2. To the rear of the 5 cylinder and in line therewith is the pivotal shaft 3 which carries the two paper finger pivotal supports 4. The rod 3 is rigidly mounted on the carriage and is provided with a semi-circular groove 5 in which the 10 pin 6 lies. The bow shaped spring 7 yieldingly holds the pin 6 in groove 5, the pin being provided with the reduced ends 8 to enter corresponding grooves in the support 4.

15 The supports 4 are bored out to take over the rod 3 and are each provided with two semi-circular grooves to take in the reduced ends 8 of the pin 6. This device is the well known one of the Underwood type- 20 writer, for holding the paper fingers 9 spring-pressed against the platen and whereby they may be rotated upward and back to release the paper. Since the parts above mentioned are old and well known, further 25 description is believed unnecessary.

As above stated, the paper finger supports of the Underwood typewriter, including their carrying arms are made in a single piece and in right and left hand pairs. 30 Hence, while said paper fingers are adapted to be turned upward and back, they cannot be turned outwardly out of the field of the work sheets.

In my improved paper finger device, the 35 carrying arms form a part of the paper fingers and are hinged to the support 4 to permit of turning them together with the paper guiding fingers 9 which they carry, out of the field of the work sheets, while the 40 paper finger supports are still in their normal holding position. This results from the vertical position occupied by the hinge pins while the fingers are in normal paper holding position.

45 In the Underwood device, in lifting the paper finger up and off from the platen, the pin 6 escapes from its semi-circular groove 5 in the pivotal shaft 3, owing to the yielding of the bow shaped spring 7, and there is no 50 tendency of the parts to be restored to their work holding positions by the spring when lifted.

Referring to my improved paper finger device, parts of the Underwood paper finger device heretofore in use may be employed, if desired, in making my improved paper finger devices. Thus there may be removed from the upper end of a regular Underwood 55 paper finger support plate, corresponding to the plate 4^a, which extends forwardly from its pivotal support 4 and overlies the platen as shown in the drawings, the bent in or overlapping arm which extends into the field of the work sheets and which carries 60 the paper guiding finger, corresponding to

the paper guiding finger 9, which finger carries the rubber roller 10. Such modified support I mount on the carrying shaft 3 as usual, with spring 7 and holding pin 6. Then I preferably provide a reinforcing 70 bracket 11, as shown (although the support may if desired be employed alone, or the carrier made in a single piece, if preferred). This reinforcing bracket is provided with a forwardly extending plate 11^a which overlies 75 the platen beside the plate 4^a and is riveted to the plate 4^a by rivet 12 and by the two rivets 13, 13, the latter also riveting on the retaining spring or retaining element 14.

The upper end of bracket 11 is bifurcated 80 and curled into one member 15 of a hinge joint. Into the bifurcation thus provided, is inserted the other member 16 of the hinge joint. This member is on the supporting or carrying arm 17 which carries the paper 85 guiding finger 9. The two members are fastened together by hinge pin 18. The supporting arm 17 is provided with a finger 19 to catch into the locking notch 20 of the spring 14 to normally lock down the paper 90 guiding finger 9, and the supporting arm 17 is provided with a finger piece 21 to be employed in lifting and swinging the device. Spring 14 is provided at its upper end with a thumb piece or cupped head 22. The arm 95 17 is recessed at 23 for clearance of cupped head 22, when the arm 17 and its attached paper guiding finger 9 are swung outwardly into the full line position of Figure 4, to wholly free the work sheets from the paper 100 fingers and their supports.

In the operation of the device, the operator places the thumb of the right hand on the cupped head 22 of spring 14 and the fingers of the same hand under the finger 105 piece 21. Then he pushes inwardly with the thumb to free the finger 19 from the locking notch 20 of spring 14. At the same time, he lifts upwardly with the fingers under finger piece 21, thereby freeing the arm 17 from the 110 spring 14 and swinging the arm and paper finger from the dotted line position Figure 4, into the full line one shown in said figure, where it is wholly out of the field of the work sheets. At the same time, he performs 115 a similar operation with the left hand on the left hand paper finger device, thus simultaneously removing both paper fingers wholly out of the field of the work sheets. It is not necessary, in thus freeing the work field of 120 the paper fingers, to swing upwardly the device, as is necessary in the device heretofore in use. The arms 17 and fingers 9 thereon can be swung directly outwardly while the supports 4 remain in their operative 125 position. Of course the supports 4 can also be swung upwardly if desired.

A function of finger 19 is to be bent upwardly or downwardly relatively to arm 17, so as to properly position the paper guiding 130

finger 9 and rubber roller 10 on the platen 2. The arm 17 can also be bent at neck 23^a for the same purpose.

When in normal holding position, both arms 17 and their paper guiding fingers 9 and rollers 10 are preferably rigidly locked down and can only be unlocked by the hand operation as above described, the springs 14 and their locking notches 20 being so formed as to constitute substantially a rigid lock. But in the return movement to normal position, the springs are so formed as to yieldingly permit such relocking movement automatically when the operator swings the arms 17 inwardly to normal holding position. Of course the fingers 17 may be held in normal position by relatively powerful springs which can yieldingly unsnap.

Structurally my improved device is much stronger than the regular paper finger device heretofore used. Such increased strength in my device resides in the reinforcing bracket 11. In my device, as in the regular Underwood, there is the regular yoked bearing. Here the forwardly extending plate is at one or the other end of the yoke, depending as to whether the paper finger be a right hand one or a left hand one.

The tendency with such yoked bearing, when pulling or pushing the plate to slide it on its way rod 3, inwardly or outwardly, on the rod, is to spring the yoked bearing. My reinforcing bracket, constitutes in effect, an oppositely disposed yoke and resists and counteracts such tendency to stretch or bend the yoked bearings.

In the form above discussed, the usual paper guiding fingers 9 and their feed rollers 10 are shown. In Figures 8 and 9, I show modified, novel and advantageous paper guiding fingers 9^a, and feed rollers 10^a which latter are much longer than the regular Underwood feed rollers 10 of Figures 1 to 7.

It will also be seen that in the modified finger, the feed rollers 10^a at their outer ends are substantially flush with the hinged ends of arms 17, and that at their inner ends they are substantially flush with the free ends of such arms. It will also be noted that the lower portions 29 of the fingers are off-set toward the outer ends of the platen. The lower portions 29 of the fingers are thus set considerably nearer to the ends of the platen than in the regular Underwood fingers. The result is that a much wider work field is attainable with the use of the modified fingers than with the use of the regular fingers, for the reason that when the supports, on which the regular fingers are mounted, are moved clear to the ends of their supporting rod, the fingers are still positioned considerably inwardly of the ends of the platen. In my device on the other hand, when the supports are placed as far apart as they will

go, the lower portions 29 of the fingers are positioned at the ends of the platen, and as a matter of fact at their outer edges overlie or project beyond the ends of the platen and the inner edges of the lower portions 29 are positioned inwardly of the platen only a relatively small distance.

Furthermore, in my modified device when the supports are moved as far apart as possible the rollers extend clear to the ends of the platen and hence a wider breadth of engaging surface against the work may be had and consequently a more perfect control of feed of the work is obtained.

The modified paper holding fingers are especially adapted to card writing, or for writing within the marginal space of the paper, as well as writing on wider sheets. If it is desired to write very near the edge of the work sheet or index cards, the fingers 85 may be spaced apart so as not to catch the work sheets or card at all when passing above the printing line, until it reaches the beveled edge 25. Then the fingers can be lifted slightly and the work sheets or cards 90 caught thereunder.

The edge 25 is beveled as shown, so as to securely feed the work sheets thereunder. For instance, if the paper fingers be so spaced apart as to catch each edge of the work sheets, when the sheets have been fed up to beveled edge 25, they readily and accurately pass thereunder, since they are always being pressed under the beveled edge 25 and paper guiding finger 9^a at a single point 100 only, and always close up to the held edges, I have found in practice, that they will not thus feed if the lower edge 25 be horizontally straight across or unbeveled, since the work sheets then tend to belly out away 105 from the held edges and thus tend to ride over and outside the wide part of such paper fingers.

The lower end of beveled edge 25 forms a junction with the vertical edge 26 at the point 27. These two edges 25 and 26 are preferably so placed that the junction 27 comes at the point which is just above the tops of the upper case letters on the type bars when at the platen, so as to catch over 115 the work sheets or index cards as soon as possible after the printing, but without collision between the upper case type characters and the wide part 28 of the paper guiding fingers, or the beveled edges 25. 120

In the claims the word "plate" is used in its broadest sense and to indicate the portion of the support, to which the arm 17 is hinged, and which overhangs the platen and is disposed laterally beyond the field of the work sheet. Any element such as a rod, bar, tube or other element that is carried by the support and acts as a means to which the finger supporting arm is hinged, may be used in lieu of the plate. 125 130

Where, in the claims, I specify a plate, all the parts of which are positioned laterally beyond the field of the work sheets at the platen, or the work field (the two terms being employed interchangeably), I do not intend to limit the plate to any particular form, but merely intend to state the fact that, whatever the particular form of the plate, it is positioned as a whole laterally beyond the work field; and by the terms positioned wholly beyond the work field laterally, or the entire plate being so positioned, I intend to convey the same meaning.

The reason for so positioning the carrying plate is so as to entirely clear the work field of all parts of the paper finger device, for erasures on the work sheet and particularly on underlying carbon copies. My invention contemplates entirely clearing the work field at the platen, of all parts of the two paper finger devices at the two ends of the platen. Thus the carrying plates are positioned at either end of the platen, laterally wholly beyond the field of the work sheets at the platen, so that when the paper finger carrying arms, which extend inwardly from their hinged connections with the carrying plates, into the work field, at either end of the platen, are swung outwardly on their jointed connections, they will move, together with their paper guiding fingers, wholly out of the work field, so that the entire work field will be cleared of all parts of the two paper finger devices; no inwardly extending portions of the carrying plates or paper fingers remaining to obstruct the lifting of the outer work sheets for correction of underlying ones.

I have used herein the terms longitudinal, transverse and lateral. I will define these terms, as employed herein and in the accompanying claims, as follows:—By the term longitudinal I mean in a direction lengthwise of the platen. The term transverse means crosswise of the platen and the term lateral means toward the sides of the machine. By the term field of the work sheet carried by the platen or field of the work sheets at the platen, or work field, I mean that portion of the length of the platen which corresponds to the distance between the overhanging plates, some portion or all of which is occupied by the work sheets, whether lying on the platen or when the upper portions of the outer sheets are swung transversely forward far enough for unobstructedly making corrections on the under sheets, while the lower portions of all the sheets are held on the platen. A distinction should be noted between the use of the terms lock, locking means, means for locking the two parts together, and locking means for normally holding the paper finger in its work holding position, on the one hand, and, on the other hand of the term a spring

pressure means to normally retain the paper finger in work-engaging relation with the platen. The latter term has a different meaning and scope than that of the former ones.

The spring pressure means which normally retains the paper finger in its work engaging relation with the platen, in my herein device, is the spring pressure means on the support. It includes the guide rod 3, with its groove 5, spring pressed pin 6, with reduced ends 8, spring 7, all operatively connected with the support 4, which latter is thereby spring-pressed so as to move its plate toward the platen, to normally retain the paper finger in work-engaging position at the platen.

It will be understood that my reinforcing yoke (designated by the reference character 11) is applicable equally with the regular Underwood paper finger device and with my hinged paper fingers. Therefore I intend my claim to such reinforcing bracket to be understood as being intended to cover both said devices.

Having thus described the invention what I claim as new, and desire to secure by Letters Patent is,

1. In a paper finger device for typewriters, the combination with the platen, of a support pivotally and slidably mounted with respect to the platen and having a plate position laterally beyond the field of a work sheet carried by the platen, a supporting arm hingedly connected to the plate and extending longitudinally of the platen into the field of the work sheet, a paper finger device carried by the supporting arm, locking means co-operating between the plate and the supporting arm to normally retain the finger in work-engaging relation with the platen, and means whereby the locking means may be released from its co-operating relation, whereby the supporting arm may be swung longitudinally of the platen out of the field of the work sheet.

2. In a paper finger device for typewriters, the combination with the platen, of a pair of supports having plates positioned laterally beyond the opposite edges of the work field at the platen, supporting arms hingedly connected to the plates and extending longitudinally of the platen into said work field toward each other, paper guiding fingers carried by the supporting arms, locks co-operating between the plates and the supporting arms to normally retain the paper guiding fingers in work-engaging relation with the platen, and means whereby the locks may be released to swing the paper guiding fingers away from each other.

3. In a typewriter, the combination with the platen, of a paper finger supporting arm, a support to which the arm is hingedly connected, said support being positioned later-

ally wholly beyond the field of the work sheets at the platen and being pivotally mounted to swing the paper finger supporting arm transversely of the platen, into and 5 out of normal position relatively to the platen, said arm extending longitudinally of the platen and being movable on its hinged connection longitudinally of the platen, both when the support is in normal position, and 10 when it is in abnormal position relatively to the platen.

4. In a typewriter, the combination with the platen, of a paper finger and a support therefor, said support being pivotally mounted 15 to swing the paper finger transversely of the platen into and out of its normal work sheet holding position, a jointed connection between the paper finger and the support, whereby the paper finger may be moved 20 longitudinally of the platen into and out of the field of the work sheet, a spring mounted on the support and provided with a notch, a finger carried by the paper finger and adapted to engage in the notch for normally 25 holding the paper finger in work-engaging position relatively to the support, and a thumb piece on the spring whereby the latter may be moved to disengage the said finger carried by the paper finger, to 30 allow of the paper finger being moved longitudinally of the platen out of the field of the work sheet.

5. In a typewriter, the combination with the platen, of a paper finger and a support 35 therefor, said support being pivotally mounted to swing the paper finger transversely of the platen into and out of its work sheet holding position, a jointed connection between the paper finger and the support, 40 whereby the paper finger may be moved longitudinally of the platen into and out of the field of the work sheet, and locking means for positively holding the paper finger in normal work-engaging position relatively 45 to the support, said locking means being releasable in all positions of the support for permitting movement of the paper finger longitudinally of the platen out of the field of the work sheet.

50 6. In a typewriter, the combination with the platen, of a paper finger and a one-part support therefor, said support being pivotally mounted to swing as a whole to move the paper finger transversely of the platen 55 into and out of its work sheet holding position, a jointed connection between the paper finger and the support, whereby the paper finger may be moved longitudinally of the platen into and out of the field of the work 60 sheets, and locking means for positively holding the paper finger in its normal work-engaging position relatively to the support, said locking means being releasable for permitting movement of the paper finger longi-

tudinally of the platen out of the field of the 65 work sheet.

7. In a typewriter, the combination with the platen, of a paper finger and a support therefor, said support being pivotally mounted to swing the paper finger transversely of the platen into and out of its work sheet holding position, spring pressure means for normally thrusting the paper finger to the platen, a jointed connection 70 between the paper finger and the support, whereby the paper finger may be moved longitudinally of the platen into and out of the field of the work sheet, and locking means for positively holding the paper finger in its normal work-engaging position 80 at the platen, said locking means being releasable to free the paper finger from the impulse of said spring pressure means tending to press it to the platen.

8. In a typewriter, the combination with the platen, of a paper finger and a support therefor, said support being pivotally mounted to swing the paper finger transversely of the platen into and out of its work sheet holding position, a jointed connection 90 between the paper finger and the support whereby the paper finger may be moved longitudinally of the platen into and out of the field of the work sheets, and locking means for positively holding the paper finger in normal work-engaging position 95 relatively to the support, said locking means being releasable for permitting movement of the paper finger longitudinally of the platen out of the field of the work sheets, the said longitudinal movement of the paper finger being wholly independent of the transverse movement of the support.

9. In a typewriter, the combination with the platen, of a paper finger and a support 105 therefor, said support being pivotally mounted to swing the paper finger transversely of the platen into and out of its work sheet holding position, spring pressure means for normally swinging the paper 110 finger to the platen, a jointed connection between the paper finger and the support, whereby the paper finger may be moved independently of the support into and out of its work sheet holding position, said 115 spring pressure means tending to open the joint, and locking means operating to hold the joint closed and thereby positively holding the paper finger in its normal work sheet holding position at the platen.

10. In a typewriter, the combination with the platen, of a paper finger and a support therefor, said support being pivotally mounted to swing the paper finger transversely of the platen into and out of its 120 work sheet holding position, and a jointed connection between the paper finger and the support whereby the paper finger may be

- swung into a reversed position relatively to the platen and beyond the work field when the support is swung to move the paper finger out of its work sheet holding position.
- 5 11. In a typewriter, the combination with the platen, of a paper finger and a support therefor, said support being pivotally mounted to swing the paper finger transversely of the platen into and out of its 10 work sheet holding position, said paper finger being provided with a carrying arm extending into the work field and a paper guiding finger having its work engaging face curved to conform to and facing the platen, 15 and a jointed connection between the paper finger and the support whereby the paper finger may be swung beyond the work field and into such relation with the platen that the work engaging face of said paper guiding finger may be curved oppositely to and faced away from the platen, when the support is swung to move the paper finger out of its work sheet holding position.
12. In a typewriter, the combination with 25 the platen, of a two-part paper finger device, one part being a support and being pivotally and slidably mounted relatively to the platen and including a plate extending forwardly over the platen, the entire plate being positioned laterally beyond the work field, the other part being a paper finger, a hinged connection between the paper finger and the plate member of the support, said support including means for spring- 30 pressing the paper finger normally to the platen, and co-operating means between the paper finger and the plate member of the support effective in the normal position of the parts, to transmit the force of the spring-pressure means to the paper finger at the 35 platen.
13. In a typewriter, the combination with the platen, of a two-part paper finger device, one part constituting a support, and 45 the other part constituting the paper finger, the support being pivotally mounted relatively to the platen, whereby the paper finger may be swung transversely of the platen into and out of work-engaging position relatively to the platen, the paper finger being pivotally mounted on the support in such 50 relation thereto that it may be swung longitudinally of the platen into and out of work-engaging position relatively to the platen, the swinging movement of the support and the swinging movement of the paper finger being wholly independent of each other, and locking means for normally holding the paper finger in work-engaging position 55 relatively to the support, said locking means being releasable for allowing movement of the paper finger relatively to the support out of work-engaging position, said locking means operating to automatically 60 lock the paper finger when the latter is 65

moved into work-engaging position relatively to the support.

14. In a typewriter, the combination with the platen, of a two-part paper finger device, one part being a paper finger and adapted to swing at right angles to the other part to move the paper finger into and out of the work field, the other part being a support positioned wholly outside of said work field, adapted to swing the paper finger into and out of work-engaging position relatively to the platen, the two said movements being wholly independent of each other.

15. In a paper finger device for typewriters, the combination with the platen of 80 a paper finger carrying arm movable into and entirely beyond the work field, and means movable transversely of the platen to which the carrying arm is movably joined, said means being wholly beyond the 85 work field.

16. In a paper finger device for typewriters, the combination with the platen, a guide rod at the rear of the platen, a support having a yoked bearing on the rod and 90 a forwardly reaching plate of a paper finger carrying arm hinged to the plate in front of the platen, for radial movement into and out of the field of a work sheet carried on the platen and locking means between the 95 plate and the carrying arm to normally maintain the paper finger in its operative work holding position.

17. In a paper finger device for typewriters, the combination with the platen, a 100 guide rod at the rear of the platen, a support having a yoked bearing on the rod and a forwardly extending plate, of a reinforcing bracket for the support, oppositely yoked at its inner end to the rod and at its 105 outer end provided with a forwardly extending plate rigidly attached to the plate on the support, and a paper finger carrying arm hinged to one of the plates in front of the platen, for radial movement into and out 110 of the field of a work sheet carried on the platen.

18. In a paper finger device for typewriters, the combination with the platen, a guide rod at the rear of the platen, a support having a yoked bearing on the rod and 115 a forwardly extending plate, of a reinforcing bracket for the support, oppositely yoked at its inner end to the rod and at its outer end provided with a forwardly extending plate rigidly attached to the plate on the support, and a paper finger carrying arm hinged to one of the plates in front of the platen, for radial movement into and out 120 of the field of a work sheet carried on the platen and locking means between the plates and the carrying arm to normally maintain the paper finger in its operative work holding position.

19. In a paper finger device for type- 130

- writers, the combination with the platen, of a support pivotally mounted with respect to the platen and having a plate positioned laterally beyond the field of a work-sheet carried by the platen, a carrying arm on the plate extending longitudinally of the platen into the said work field, a paper guiding finger carried by the arm, comprising an intermediate laterally extending part with an upwardly reaching finger at its inner end fastened to the carrying arm and a downwardly reaching work engaging finger at its outer end, the two said fingers being relatively off set, the said intermediate part being beveled upwardly and inwardly at its lower edge, from its junction with the work engaging finger to the inner end of the carrying arm, and being provided with a longitudinally extending feed roll mounted thereon.
20. In a typewriter, the combination with the platen and its printing line, of a paper finger carrying arm, a support to which the arm is connected, said arm extending longitudinally of the platen into the field of a work sheet carried thereon, a paper guiding finger fastened on the inner end of said arm, having its work engaging end off-set outwardly toward the edge of the field of the work sheet at the printing line, a beveled edge part on the paper guiding finger between the printing line and the carrying arm, extending inwardly from the said off-set end to the inner edge of the paper guiding finger, and a feed roll mounted on the said part of the paper guiding finger, below the carrying arm and above the printing line.
21. In a typewriter, the combination with the platen and its printing line, of a paper finger device comprising a support pivotally mounted at the rear of and extending forwardly over the platen and having a carrying arm which extends longitudinally of the platen into the field of a work sheet carried thereon, a paper guiding finger carried by the arm at its inner end, the paper guiding finger being offset outwardly below the arm, toward the edge of the field of the work sheet at the printing line, a beveled edge part on the paper guiding finger above the printing line extending inwardly from the offset part to the inner end of the paper guiding finger and a feed roll 55 below the supporting arm mounted on said beveled edge part of the paper guiding finger.
22. In a typewriter, the combination with the platen, of a two-part paper finger device, one part including a paper finger, and being pivoted to the other part in such manner that the paper finger may be swung into and out of the work field, and means for locking the two parts of the device together when the paper finger is in normal work-engaging position relatively to the platen, said locking means being releasable when the paper finger is in said work engaging position.
23. In a typewriter, the combination with the platen, of a two-part paper finger device, one part including a support movable transversely with regard to the platen, and the other part including a paper finger movable longitudinally with respect to the platen, a hinged connection between the two parts of the device, and locking means effective to lock the paper finger when in normal work-engaging position relatively to the support, and ineffective irrespective of the position of the support when the paper finger is out of normal work-engaging position relatively to the support.
24. In a typewriter, the combination with the platen, of a two-part paper finger device, one part including a support, and the other part including a paper finger movable out of work engaging relation relatively to the support irrespective of the position of the support, a hinged connection between the support and the paper finger, and a locking means automatically operating to lock the paper finger relatively to the support when the paper finger is moved into work-engaging relation relatively to the support.
25. In a paper finger device for typewriters, the combination with the platen, a paper finger in work holding position at the front of the platen, a guide rod at the rear of the platen, a support for the paper finger having a yoked bearing on the rod and a forwardly reaching plate carrying the paper finger, of a bracket for the support, oppositely yoked at its inner end to the rod and at its outer end rigidly secured on said plate and serving to constitute a reinforcement to strengthen the device.

FREDERIC W. HILLARD.
